UNITED STATES PATENT OFFICE.

GEORGE L. PRICHARD AND HERBERT HENDERSON, OF PORT ARTHUR, TEXAS, AS
SIGNORS TO GULF REFINING COMPANY, OF PITTSBURGH, PENNSYLVANIA, A COR-
PORATION OF TEXAS.

DISTILLATION OF OILS WITH CATALYSTS.

Application filed November 28, 1921. Serial No. 518,197.

This invention relates to distillation of oils with a catalyst; and it comprises an improvement in the distillation of petroleum oils with a catalyst, such as anhydrous aluminum chlorid, for the purpose of producing oils of lowered boiling point, wherein a body of oil and catalyst (aluminum chlorid) is established and maintained at a temperature sufficient to cause free ebullition with production of vapors and the catalyst is withdrawn from the bath prior to its complete exhaustion or conversion into a coky sludge, delivered to a suitable heater device and is then exposed to a temperature at which the catalyst will volatilize, the vapors of the catalyst so formed (and any oils withdrawn with it) being recovered in any suitable way but advantageously by returning to said bath; all as more fully herein-
20 after set forth and as claimed.

As is well known, it is possible to produce oils of lowered boiling point by distilling high boiling petroleum oils with catalysts usually anhydrous reactive chlorids, bro-
25 mids, etc. such as iron chlorid, zinc chlorid and, particularly, anhydrous aluminum chlorid. This fact is utilized in the produc-
30 tion of gasoline and similar products from higher boiling oils, such as gas oil, kerosene, etc. In this operation success depends upon attention to many minutiae. Anhydrous aluminum chlorid (the catalyst now exten-
35 sively used) is not particularly soluble in oils, hot or cold, and when a small amount of aluminum chlorid, say, 5 per cent, is added to a petroleum oil, the aluminum chlorid melts down with a portion of the oil to form a heavy oily liquid underlying the rest of the oil. When this heavy liquid is kept
40 stirred through the rest of the oil and the mixture is heated, at a certain temperature, which is often below the natural boiling point of the oil under treatment, the mass enters into free ebullition with production
45 of vapors of oil of a lowered boiling point. Usually, the bath of oil and aluminum chlorid is kept replenished by additions of fresh oil in proportion to the formation of vapors. The operation may be continued in
50 this way until the aluminum chlorid loses its activity and is converted into a relatively inert coky or sludgy mass. At this time it is removed and replaced by fresh chlorid. Ordinarily, the proportion of aluminum

chlorid employed is such as to constitute 55 about 5 per cent of the mass of oil tempo-
rarily under treatment, though the per-
centage as regards the total oil undergoing
treatment is of course considerably less, since
the bath is usually replenished during the 60 treatment and prior to the exhaustion of the
charge of chlorid. The coky or sludgy re-
sidue withdrawn from the still is subjected
to a suitable treatment to recover aluminum
chlorid in an active condition for reuse. 65 Ordinarily it is placed in a retort and heat-
ed, distilling off first the oil which is present
and then the aluminum chlorid. Recovery
may be facilitated and aided by the use of a
little chlorin or chlorin containing gas such 70 as hydrochloric acid.

In the described operation, there is con-
siderable loss because of the changes under-
gone by the aluminum chlorid in the re-
sidues in handling. And in the distillation 75 process described the aluminum chlorid is
not utilized to its fullest extent, it becom-
ing masked so to speak by carbon when the
process is carried so far as to leave a coky
or sludgy residue.

Aluminum chlorid is very sensitive to the
action of moisture by which it is hydrated
and decomposed, giving alumina and, if the
mass is hot, vapors of HCl. Hydrated alu-
minum chlorid has no catalytic activity upon 85
oils and cannot be reconverted to the an-
hydrous form. It is very difficult to avoid
exposure of the aluminum chlorid to damag-
ing amounts of water vapor in transferring
the sludge from the stills to the recovery ap- 90
paratus.

In the production of gasoline, etc., there
is a progressive change in the characteris-
tics of the aluminum chlorid in the still.
At first it is, as stated, a heavy viscid liquid 95
and finally it becomes a tarry or coky mass.
At intermediate times, it is of an inter-
mediate character. The converting activity
is very great at first but rapidly diminishes
as the aluminum chlorid thickens. Whether 100
this be because of the increased difficulty in
securing a large area of contact between the
oil body and the thickened aluminum chlo-
rid, or whether it be because of a real di-
minution in converting power, the fact is as 105
stated.

We have found that in the recovery there
is much the same phenomenon—the alumini-

num chlorid is much more rapidly and easily recovered from the oily material in the earlier stages of distillation than from the thicker material of later stages; and we have 5 found that this increased ease of recovery makes it economical to interrupt the utilization of the aluminum chlorid at a time when its activity is far from exhausted, remove it and recover it. If the aluminum 10 chlorid be removed as a more or less fluid liquid prior to its reaching the asphaltic or coky consistency and be placed in a retort and distilled, the aluminum chlorid goes over with the oil vapors at a much lower temperature than would be necessary in recovering 15 aluminum chlorid from an asphaltic or coky residue.

While we do not commit ourselves to any theory as regards the reason for this easier 20 recovery, we may call attention to the fact that, as stated, when aluminum chlorid is added to hot oil it melts down with a portion of the oil to a heavy liquid. This is apparently a combination of the oil and aluminum chlorid. It is perhaps possible that 25 during the progress of the distillation the character of the oil associated or combined with the aluminum chlorid progressively changes, and that in the exhausted aluminum chlorid the combination is with hydrocarbons of a more or less asphaltic nature; such a combination that aluminum chlorid 30 distills from it with difficulty.

By removing the aluminum chlorid 35 sludge at an intermediate stage of exhaustion, it is of such consistency as enables its ready transfer through pipes to recovery apparatus without exposure to air. This precludes the material loss occurring in the ordinary methods of handling.

The aluminum chlorid coming as vapors 40 from the recovery apparatus is highly active and suited for reuse. In distilling this character of residue, however, the vapors of aluminum chlorid are ordinarily associated 45 with oil vapors. The two may be condensed together to form a heavy, oily liquid like that originally formed in the still. This liquid may be returned to the still. Or, the hot oil and aluminum chlorid vapors coming 50 from the recovery apparatus may be sent direct to a still operating with aluminum chlorid to take part in the operation of such still. In so doing, looked at in one way, the function of the recovery apparatus is largely 55 that of elimination of coky and asphaltic hydrocarbons which would otherwise finally mask the activity of the aluminum chlorid in the still.

In the present invention we contemplate 60 running the gasoline-making operation at high speed, using nothing but highly active aluminum chlorid. And we increase the amount of aluminum chlorid present above 65 the usual 5 per cent, giving as high as, say,

10 per cent. Where the recovery apparatus has a direct vapor connection with the still, much of the aluminum chlorid is in cyclic circulation, passing from the still to the recovery apparatus and thence back; and the 70 10 per cent figure refers merely to the amount in the still—to a proportion of 10 per cent of aluminum chlorid to the weight of oil in the still undergoing distillation. And by our method we may eliminate the 75 formation of coky residues in the stills.

In the accompanying drawings showing one form of a specific embodiment of our invention, and illustrating an apparatus within the purview of our invention.

Figure 1 is a view partly in vertical section and partly in elevation;

Figure 2 is a top plan view of Figure 1 and

Figure 3 is a segmental enlarged horizontal section through the converter or still at the point of inlet of oil.

In the drawings, 1 indicates a furnace which may be divided into preheating compartment A and superheating compartment B divided by the bridge-wall 2. This furnace is preferably of fire-brick or the like 3 suitably insulated with kieselguhr or the like 4, and is provided with the oil and steam burner 5 or other heating means. The preheating compartment A comprises a plurality of tubes 6, here shown as horizontal, through which the oil flows. Oil is admitted to the preheater by line 7 leading from the pump 8. From the preheater the oil 100 flows to the superheater compartment B in the tubes 9 located therein and from the tubes 9 the oil flows by means of line 10 to the still or converter to be described. When the material is to be constantly circulated it 105 is removed from the converter by line 11 and sent to the pump 8. We may use one or more heaters. The line 10 may be branched with the valved pipe 13 having the down pipe 14 extending near the bottom of 110 the converter, and may also be provided with the valved branch 16 extending into the upper part of the converter preferably below the level of the contents.

The converter or still is indicated as a 115 whole by 17. It comprises a steel or other suitable tank 18 covered with insulation material such as kieselguhr, asbestos or the like 19 and is provided with a cone-shaped bottom forming a settling basin 20. This converter or still is mounted upon the standards or supports 21 suitably braced as at 22. It may be provided with stirring mechanism comprising a shaft 23 suitably journaled in the journal 24 at the bottom of the still and passing through the packing or stuffing box 25 at the top. Journal 26 is carried by the brackets 27 and to the shaft at the top is keyed beveled gear 28 meshing with the pinion 29 driven by pulley 30 and in turn 120 125 130

driven by the belt or chain 31 leading to the motor 32. The shaft may be braced inside the still by the arms 33. The still or converter may be provided interiorly with the 5 arms 34 between the paddle blades 35 carried by the shaft 23. Vapors of lower boiling hydrocarbon together with some aluminum chlorid and the combination of aluminum chlorid with higher boiling oils go to the 10 preliminary air cooled condenser 36 through vapor line 37, condensed products being backtrapped to the still through line 38. Vapors leaving the preliminary air cooled condenser 36 go to the final air cooled 15 condenser 39, condensates therefrom returning to the backtrap line 38 by means of the line 40. The backtrap line 38 preferably leads below the level of the contents of the still. The air cooled condensers 36 and 39 20 are provided with thermometers 41 in order that the temperature of the vapors may be observed. In aluminum chlorid distillation processes the temperature of the vapors leaving the final air cooled condenser should 25 not be materially above 350° F., since at and below that temperature aluminum chlorid, and its compounds with hydrocarbons, will condense and go back to the still, whereas at a higher temperature they will not condense, 30 but will pass over with the vapors of lower boiling oils. From the final air cooled condenser vapors of lower boiling hydrocarbons flow by line 42 to the coils 43 in the water cooled condenser 44, suitably mounted 35 by means of supports 45 upon the condenser box foundation 46. From the coils in the condenser the condensed lower boiling oils flow by means of line 47 to a storage tank past the liquid seal 48, any non-condensed 40 gases escaping through the line 49.

Aluminum chlorid and higher boiling oil may be admitted to the still or converter through the inlet 50.

The converter at the bottom is provided 45 with the offtake 51 from which the residual oil and aluminum chlorid may be withdrawn. According to our process the aluminum chlorid is withdrawn with some oil before the activity of the aluminum chlorid 50 is completely spent and it is sent by means of valved line 52 to the pipe 53 leading to the retort 54. This retort may comprise a steel or other suitable tank 55 mounted upon the furnace 56 which may be provided with 55 the burners 57 and the stack 58. This retort constitutes the recovery apparatus. Volatile products leaving the retort by line 59 may go past the branch 60 into line 61 leading to the still 17 preferably into the 60 vapor space thereof. If desired the branch 60 may be used to send the volatile products from the retort to suitable condenser apparatus through line 62 and in certain stages of the operation when gases containing chlorin (HCl) are evolved, they may be sent by

line 63 to suitable apparatus where the gases may contact with aluminous material for the manufacture of aluminum chlorid therefrom.

In a specific embodiment of our invention, 70 higher boiling oil such as gas oil is fed to the converter through the charging line 50 until a sufficient quantity of higher boiling oils has been added to bring the charge level above the circulating pipe 11. The pump 75 8 is then started circulating the charge through the pipe heating unit or furnace 1 and sending it back into the converter or still through lines 10 and 14. When the charge in this converter is sufficiently heated 80 aluminum chlorid and high boiling point oil are pumped in through the charge line 50; the high boiling point oil carrying with it sufficient amounts of aluminum chlorid to equal, for instance, 10 per cent by weight 85 of the total charge in the still. The oil or gas burner 5 in the furnace is then suitably regulated to heat the oil in the tube furnace to the required temperature and we deliver the oil through circulating pipe 10 90 advantageously to a point near the bottom 95 of the converter by line 14. The stirrers 35 are then operated to keep the mixture in the unit or converter well agitated. The hot oil and vapor delivered to the converter at the bottom pass up through the body of the mixture and released vapors pass through the vapor line 37, the temperature in the converter being controlled so that the vapor leaving the final air cooled condenser shall 100 not materially exceed 350° F. as registered by the thermometer 41 in the line leading from such condenser. The vapors from this point go through the vapor line 42 into the condenser coil 43 and condensates go past the gas seal 48 through line 47 to the running or storage tank. The noncondensable 105 gases released through pipe 49 go to an absorption or compression plant.

After the converter or still has been operated to a point where gasoline to the extent of from $\frac{1}{10}$ th to 5 gallons of gasoline per pound of aluminum chlorid in the converter has been taken off, the circulation of oil 110 passing through pipe 10 and entering the bottom of the converter by line 14 is then changed by closing the valve on line 13 (Figure 3) and opening valve or line 15, thus delivering the circulating oil through line 16 115 to the top of the magma unit. The stirrers are either slowed down or stopped entirely and 25 per cent more or less of the sludge in the converter is drawn off through line 51 into the retort 54 by opening suitable 120 valves on the line. After this amount of sludge has been drawn into the retort valve on line 13 will be opened and valve on line 15 will be closed, again discharging the circulating oil to the bottom of the converter 125 through line 14. The stirrers 35 are again 130

put in operation or speeded up and an amount of aluminum chlorid charged into the unit with high boiling point oil through the line 50, such amount being equivalent 5 to the amount of aluminum chlorid drawn off in the sludge into the retort 54. This keeps the amount of aluminum chlorid in the converter as near as possible to the desired amount of 10 per cent by weight in the 10 unit. High boiling point oil may be fed in continuously through line 50. When this is done and retort 54 fired the aluminum chlorid is distilled through line 59 to the condensing chamber, kettle or a still through 15 line 62. If the vapors be sent to a condensing chamber the aluminum chlorid will be taken from such chamber, placed in a mixing kettle and mixed with high point boiling oil and pumped into a still. However, 20 the vapors from the retort 54 may be sent by line 59 to the converter, advantageously near the top thereof by line 61 and into the vapor space. These vapors will contain not only 25 aluminum chlorid, but vapors of higher boiling oil withdrawn with the sludge. This will allow the aluminum chlorid to sublime directly into the converter.

In order to take care of any hydrochloric acid or other chlorin-containing gas formed 30 in the recovery of aluminum chlorid in the retort 54, the gases going from the branch 63 may be passed over metallic aluminum or other aluminous material.

After the new aluminum chlorid has been 35 charged into the converter through the line 50 equivalent to the amount of aluminum chlorid drawn out with the sludge through line 51, the converter is operated until $\frac{1}{10}$ th to 40 5 gallons of gasoline per pound of aluminum chlorid in the charge has been distilled over. A second 25 per cent more or less of the sludge from the converter unit is drawn off into the second retort 54 to recover aluminum chlorid and the vapors from the first 45 retort are charged or sublimed back into the converter or another converter or still.

This cycle is carried out continuously in drawing off and passing the recovered aluminum chlorid back into a still with sufficient 50 new aluminum chlorid to take care of the loss.

The sludge is drawn off before it has done the maximum amount of work in the still 55 so that it is easily handled. The capacity of the gasoline over head is greater and the Baumé gravity is higher because the higher boiling oil is acted on by the new or recovered aluminum chlorid and the process is not allowed to run to a heavy sludge or a 60 coke.

The above description is given by way of example. We do not limit ourselves to the use of 10 per cent aluminum chlorid. We 65 have found in operation that 10 per cent works very well, but we may go even below

5 per cent and we have worked this process very satisfactorily with higher amounts than 10 per cent.

While we have shown four recovery retorts and a single still it is to be understood 70 that a greater or less number of retorts may be used and any desired number of stills; and that these retorts and stills may be connected in any desired way, sequence or phase. For example, one still may be delivering 75 partially exhausted aluminum chlorid to a given retort and this retort furnishing distilled aluminum chlorid and oil to another oil still, or the volatile products from a given retort may go back to the 80 still whence the aluminum chlorid was withdrawn.

The temperature required in recovering aluminum chlorid from partially exhausted residues, as contemplated in the present invention, varies with circumstances, and particularly with the age, that is, the degree of exhaustion of the chlorid, but in all cases is much lower than that necessary in recovering chlorid from coky or asphaltic 90 residues of practically exhausted activity.

One condition affecting the temperature needed in recovery is the amount and character of the oil accompanying the sludge to the retorts, or supplied with it. Other 95 things being equal, the more there is of this oil and the easier it distills, the lower is the recovery temperature, since oil vapors carry aluminum chlorid vapors forward with them. Sometimes a substantial degree 100 of recovery may be had at a temperature range as low as 350° to 400° F.; and sometimes temperatures as high as 500 or 600° F. are needed. In a general way, it may be said that with residues of proper character, 105 it is not necessary to go as high as cracking and coking temperatures, say 700° or 800° F. But when the recovered vapors of aluminum chlorid and oil are not to be used immediately temperatures higher than 800° 110 F. may be used in the recovery retort.

What we claim is:—

1. The process of converting higher boiling oils into lower boiling oils which comprises distilling the higher boiling oils in 115 the presence of anhydrous aluminum chlorid, withdrawing from the mixture used aluminum chlorid in the form remaining after its activity is partially spent, heating the withdrawn aluminum chlorid in such form and 120 passing the volatile products of such heating to the vapor space above the mixture of aluminum chlorid and higher boiling oil undergoing conversion.

2. The process of simultaneously converting higher boiling oils into lower boiling oils with the aid of anhydrous aluminum chlorid and recovering aluminum chlorid for use in the said conversion, which comprises establishing a body of higher boiling oil 125 130

and aluminum chlorid, tapping from the lower portion of said body a settled mixture of the higher boiling oil and aluminum chlorid, heating such tapped off mixture, 5 and passing the volatile products of such heating to the vapor space above the body of anhydrous aluminum chlorid and higher boiling oils undergoing conversion.

3. In the conversion of oils by aluminum chlorid, the process which comprises distilling a high boiling oil in the presence of active aluminum chlorid until a distillate of not substantially less than one-tenth gallon and not substantially more than five 10 gallons per pound of aluminum chlorid present is obtained, withdrawing aluminum chlorid in the form resulting from distillation to said extent, recovering from said withdrawn material aluminum chlorid in 15 active form and delivering it to the high boiling oil undergoing distillation. 20

4. In the conversion of oils by aluminum chlorid, the process which comprises distilling a high boiling oil in the presence of active aluminum chlorid until gasoline of 25 not substantially less than one-tenth gallon and not substantially more than five gallons per pound of aluminum chlorid present is obtained and the aluminum chlorid in the sludge produced is in a form sufficiently 30 oily for transmission through a pipe line, withdrawing aluminum chlorid in the form resulting from distillation to said extent and adding aluminum chlorid and oil to replenish losses by distillation and the withdrawal of aluminum chlorid. 35

In testimony whereof we have hereunto signed our names at Port Arthur, Texas, this 25th day of November, 1921.

GEORGE L. PRICHARD.
HERBERT HENDERSON.
